卷之三

UNITED STATES PATENT OFFICE.

HENRY L. JOHNSON, OF DAWSON, MINNESOTA.

HOLDER.

Application filed August 25, 1922. Serial No. 584,375.

To all whom it may concern:

Be it known that I, HENRY L. JOHNSON, a citizen of the United States, residing at Dawson, in the county of Lac Qui Parle 5 and State of Minnesota, have invented new and useful Improvements in Holders, of which the following is a specification.

This invention relates to improvements in holders especially designed for holding 10 crochet thread in a manner to permit of the same being freely unwound without tangling or knotting.

Another object of the invention is the provision of a holder in which the ball of 15 thread is mounted for pivotal movement adjacent a thread guide, whereby the unwinding tension of the thread will move the holder upon its pivot and keep the ball in proper position for unwinding.

With the above and other objects in view, the invention further includes the following 20 novel features and details of construction, to be hereinafter more fully described, illustrated in the accompanying drawings and 25 pointed out in the appended claims.

In the drawings:—

Figure 1 is a side elevation of a thread holder constructed in accordance with the 30 invention.

Figure 2 is a front view of the same.

Figure 3 is a top view.

Figure 4 is a longitudinal sectional view.

Figure 5 is a transverse section.

Figure 6 is a detail perspective view of 35 the spring yoke.

Figure 7 is a longitudinal sectional view of a modified form of holder in which the latter is enclosed within a receptacle.

Figure 8 is a transverse sectional view of 40 the same.

Figure 9 is a fragmentary plan view illustrating the pivotal mounting for the yoke.

Referring in detail to the drawings, 45 wherein like characters of reference denote corresponding parts, in the form of the invention shown in Figures 1 to 6 inclusive, there is provided a flat base 11 having its opposite side edges rolled as at 12 for attachment to substantially parallel arms 13, having one of their ends formed into eyes 14. The opposite ends of the arms 13 extend inwardly toward one another and are shaped to provide a substantially semi-circular arm 15 having at its free end a stationary guide 16. The ends of the arms

13 adjacent the eyes 14 are connected by a rod or wire 17 and the adjacent end of the base 11 is rolled over this rod or wire.

The construction just described provides 60 a firm base or support, which may rest upon a table or other article, or which may be supported by a cord or the like threaded through the eyes 14.

The holder may be secured to a suitable 65 support and for this purpose there is provided an eye 15' at the juncture of the base and the semi-circular arm 15. This eye and the eyes 14 are arranged for the passage of screws or similar fastening devices, so that 70 the latter may be held against accidental movement.

Mounted upon the base 11 is a pivot pin 18 and for this purpose there is provided spaced transversely extending arms 19, 75 whose outer ends 20 engage around the rolled edges 12 of the base, while the intermediate portions of these arms 19 are provided with eyes 22 to receive the pivot pin 18. The eyes 22 are spaced apart to receive 80 a loop 23 which forms a part of a pivotally mounted spring yoke. Extending from the loop 23 are oppositely disposed arms 24, whose outer ends extend at right angles to provide spaced substantially parallel arms 85 25. The arms 25 extend inward as shown at 26 to provide spacing portions from which extend substantially parallel portions 27, which carry pintles or trunnions 28. Removably mounted upon these pintles or 90 trunnions 28 are the opposite ends of spool sections 29 which are adapted to extend within the opposite end openings of a ball of thread 30 (such as the usual ball of 95 crochet thread) and these spool sections carry flanges 31.

After the thread has been passed through the guide loop 16, a pull upon the thread will cause the ball to move pivotally upon the pivot pin 18 as the thread passes from one to the other end of the ball during its unwinding action, so that the ball 30 will be in position at all times to permit of a free unwinding action of the thread.

In Figures 7 to 10 inclusive, the device is 100 shown within a container, the container illustrated being of cylindrical formation as shown at 32. One end of this container is open and is normally closed by a closure 33 and this closure is provided with an extension 34 which is adapted to enter the container when the closure is in position.

The extension 34 provides a base for the holder upon which the spring yoke previously described is pivotally mounted. This yoke is identical with the yoke shown 5 in Figure 6 of the drawings and its loop 23 receives the trunnion 35, which is mounted in spaced ears 36 carried by the base 34. The ears 36 are formed of a single piece 10 of sheet metal bent to provide substantially parallel portions which define the ears 36, a spacing portion 37 and outwardly extending flanges 38. The base 34 is slotted to provide tongues 39 and the latter are bent over the flanges 38 so as to hold the 15 spaced ears to the base 34. The receptacle 32 is provided with an opening 40 which forms a guide for the passage of the thread, similar to the guide loop 16 previously mentioned, the said loop 16 and opening 40 20 being stationary with respect to the bases upon which the pivoted spring yokes are mounted.

The invention is susceptible of various changes in its form, proportions and minor 25 details of construction and the right is herein reserved to make such changes as properly fall within the scope of the appended claims.

Having described the invention what is 30 claimed is:-

1. A holder embodying a base, a transversely pivoted yoke mounted thereon, a holder carried by the yoke and adapted to removably support a ball of thread and a 35 stationary thread guide located intermediate the ends of the ball.

2. A holder embodying a base, a trans-

versely pivoted yoke mounted thereon and including spaced spring arms, means located at the free ends of said arms for removable engagement with a ball of thread and a stationary thread guide located intermediate the ends of the ball. 40

3. A holder embodying a base, a transversely pivoted spring yoke mounted thereon and including oppositely and outwardly extending arms, a pivot loop at the inner ends of said arms, parallel arms extending at right angles from the outer ends of the oppositely extending arms, means located at the free ends of the parallel arms for removable engagement with a ball of thread and a stationary thread guide located intermediate the ends of the ball. 45

4. A holder embodying a base, a transversely pivoted spring yoke mounted thereon and including oppositely and outwardly extending arms, a pivot loop at the inner ends of said arms, parallel arms extending at right angles from the outer ends of the oppositely extending arms, trunnions located at the free ends of the parallel arms, flanged spool sections removably engaging the trunnions and a stationary thread guide located between the flanged spool sections. 50

5. A holder comprising a receptacle having a guide opening therein a closure for the same, a transversely pivoted yoke carried by the closure and a holder carried by the yoke and adapted to removably support a ball of thread for passage through the 55 guide opening in the receptacle.

In testimony whereof I affix my signature.

HENRY L. JOHNSON.
